UNITED STATES PATENT OFFICE.

WILLIAM R. MILLER, OF PARK PLACE, PENNSYLVANIA.

BEARING BOX FOR MINE CARS.

Application filed September 15, 1921. Serial No. 501,009.

To all whom it may concern:

Be it known that I, WILLIAM R. MILLER, a citizen of the United States, residing at Park Place, in the county of Schuylkill and State of Pennsylvania, have invented certain new and useful Improvements in Bearing Boxes for Mine Cars; and I do declare the following to be a full, clear, and exact description of the invention, such as will enable others skilled in the art to which it appertains to make and use the same.

This invention relates to an improved bearing box for use in connection with mine cars and one object of the invention is to provide a bearing box so constructed that it may be mounted upon a longitudinally extending under-beam of the mining car without it being necessary to pass bolts up through the bottom of the car. At the present time, it is customary to secure the bearing boxes by means of bolts which pass up through the bottom of the car and through the sheet metal body portion of the car. When it is necessary to renew the sheet metal body portion, it is then necessary to form holes in the sheet metal so that the securing bolts may pass through them and it has been found to be exceedingly difficult to properly place these holes. By means of the improved bearing box disclosed in the accompanying drawing, the bolts may pass transversely through the under-beam of the car and therefore the sheet metal body portion of the car can be renewed without it being necessary to remove the securing bolts for the bearing boxes.

Another object of the invention is to provide a bearing box in which the end portions of the brass bearing block will extend through the side portions of the box or housing where they may be readily seen and danger of their not being removed at the proper time avoided.

Another object of the invention is to provide improved means for holding the brass bearing block against movement longitudinally of the axle and against rotary movement about the axle.

Another object of the invention is to provide an improved type of bearing box having the box or housing properly positioned beneath a supporting bar with which the end portions of the box or housing are removably and pivotally connected, the box or housing being so constructed that no special

care is necessary in putting the box or housing in place.

Another object of the invention is to provide the box or housing with an improved construction providing pockets or compartments in which lubricant applying brushes may be placed, a brush being only placed in one compartment and this brush applying the lubricant to the side portions of the axle.

Another object of the invention is to so construct the supporting bar and housing that the lubricating oil may be fed through a passage formed in the supporting bar and drop down onto a partition above the brush, the partition being provided with a groove so that the oil will be fed onto the brush and absorbed by this brush.

Another object of the invention is to provide a bearing box which can be readily applied to a car body and which will be securely held in operative position but may be very readily taken apart for cleaning or repair purposes and very easily and quickly put together.

This invention is illustrated in the accompanying drawings, wherein:

Figure 1 is a view in side elevation showing the improved bearing in position for use.

Figure 2 is a view in side elevation showing the structure of Fig. 1 but looking at the inner side thereof instead of the outer side.

Figure 3 is a longitudinal sectional view through the structure of Figs. 1 and 2.

Figure 4 is a transverse sectional view taken along the line 4—4 of Fig. 1.

Figure 5 is a transverse sectional view taken along the line 5—5 of Fig. 1.

Figure 6 is a transverse sectional view taken along the line 6—6 of Fig. 3.

Figure 7 is a perspective view of the supporting bar which is secured upon the under-beam of the car body.

Figure 8 is a perspective view of the brass bearing block.

Figure 9 is a perspective view of the box or housing carried by the supporting bar.

Figure 10 is a perspective view of the spring which holds the brush in proper engagement with the axle.

This improved bearing is for use in connection with a mine car having a body portion indicated in general by the numeral 1 and having at each side a longitudinally extending underbeam 2. The axles which extend beneath the car will be mounted by

- means of the improved bearing boxes, it being understood that one of the bearing boxes will be provided for each end portion of the axle.
- 5 This bearing is provided with a supporting bar 3 which is U-shaped in cross section or end elevation as shown in Figs. 4 and 5 and has its side walls 4 extending up along the sides of the underbeam 2. Securing bolts 5 are passed through the walls 4 and underbeam 2 and will thus serve to securely but releasably hold the supporting bar in place. From an inspection of Figs. 4 and 5, it will be readily seen that the bearings may be easily removed without disturbing the sheet metal body portion of the car and also that the sheet metal body portion of the car may be replaced without the bearings being disturbed.
- 10 When a coal car is in use, it is customary to shift the same out of a horizontal position so that the coal may readily pass out of the car and this would place undue strain upon the bolt side which extends transversely through the underbeam 2. Therefore, the supporting bar 3 has been provided with a transversely extending rib 6 which is rectangular in cross section as shown in Fig. 3 and is positioned in a correspondingly shaped groove 7 formed in the underbeam. The supporting bar will thus be held against movement longitudinally of the underbeam and strain will be removed from the securing bolts.
- 15 The brass bearing block 8 which is shown in perspective in Fig. 8 is placed beneath the supporting bar 3 and will rest upon the axle 9 as shown in Fig. 3. This bearing block 8 is positioned between the strips 10 which extend transversely of the supporting bar and these strips 10 are provided with finger extensions 11 which fit into the recesses 12 formed in the bearing block. It will thus be seen that the bearing blocks will be securely held against movement longitudinally of the axle and will also be held against any tendency to turn with the axle. One end of the bearing block is engaged by a depending flange 13 which extends from the inner side of the supporting bar. This flange 13 serves not only to assist in holding the block against longitudinal movement but also serves as a guard to prevent dust and fine coal from working into the bearings through the inner ends thereof. The outer side portion of this supporting bar is cut as shown at 14 thus permitting the wheels 15 to rotate freely without any chance of binding. In order to strengthen the supporting bar and prevent it from being weakened by this cutout, there has been provided a strip 16 which extends in the corner portion thereof.
- 20 The housing 17 which is known as the box 65 is provided with end walls positioned between the side walls. These side walls are provided with cutouts 18 to receive the axles and permit the ends of the brass bearing blocks to extend through these inner and outer sides of the housing or box. It will thus be seen that these ends of the brass bearing blocks can be readily seen and easily inspected to ascertain whether or not they have worn a sufficient amount to need renewing. Inwardly extending sleeves 19 extend from the upper corner portions of the side walls and above the upper edges of the end wall of the housing and will fit against opposite ends of the sleeves 20 which extend downwardly from the supporting bar 3. It will thus be seen that when the securing pins 21 are put in place, the housing will be securely held in an operative position but that when desired one of the securing pins may be removed and the housing swung downwardly to an inoperative or open position.
- 25 In order to provide compartments in the housing for carrying a lubricant applying brush, there has been provided partitions 22 and 23. The space between the partitions 22 and 23 form the pockets 24 with the partitions 22 forming the lower walls of the pockets or compartments and the partitions 23 forming the upper walls of the compartments. These upper walls will each be provided with grooves 24' which are so located that the housing may be put in place with either side outermost and one of the grooves 24' will be positioned beneath an oil passage 25 formed in the outer side portion of the supporting bar. When oil is fed through the passage 25, it will drop down into the groove 24' beneath it or upon the upper partition 23 adjacent this groove and will pass through the groove and down onto the applying brush 26 positioned in this pocket or compartment. While two of these pockets or compartments are provided, there will be only one brush provided as it is only necessary to apply oil to one side of the axle. The two pockets are provided for convenience in applying the housing. The brush 26 is formed from layers of felt which will readily absorb the oil and these layers are securely connected in any desired manner so that a good brush will be provided. In order to hold the brush in proper engagement with the axle, there has been provided a strip 27 which is placed in the pocket or compartment before the brush is put in place. A spring strip 28 is secured to this strip 27 and will serve to move the strip 27 outwardly and thus apply pressure to the brush to force it outwardly and hold the brush in proper engagement with the axle.
- 30 When the bearing is in use, it will be assembled as shown and the bearing block 8 will rest upon the axle. As the axle rotates with the wheels, the oil will be applied to the axle and thus the axle will be kept very well

lubricated. When it is necessary to replenish the oil, it is simply necessary to feed this oil through the oil passage 25. The brush can thus be thoroughly soaked with oil and further a surplus supply of oil may be supplied by pouring in enough oil to fill the compartment in which the brush is placed. When it is necessary to replace the brush or when it is desired to clean the housing or brush, one of the pins 21 can be removed and the housing swung downwardly. The cleaning can then be performed and if desired a new brush put in place and the housing then swung upwardly to the operative position and secured. When it is desired to remove the brass bearing block or bushing block as it may be called, the car can be jacked up after the housing has been released and swung downwardly to the inoperative position. This will move the strips and finger extensions out of engagement with the bushing block and the block can then be removed and a new one put in place. The car can then be lowered and when the block 8 is in the proper position, the housing can be again swung upwardly to the operative position and secured. It will be further noted that if desired, the body portion of the car can be raised after the bolts 5 have been removed

and the wheels, axles and bearings removed 30 bodily from the car.

I claim:

1. An axle mounting comprising a support, a housing having its end portions pivotally and removably connected with said support whereby either end of said housing may be released and swung downwardly to an inoperative position, said housing having end walls recessed to receive an axle, and upper and lower partitions in 40 the side portions of said housing forming brush-receiving pockets extending longitudinally in the side portions of the housing and intermediate the height thereof and between the end walls thereof. 45

2. The structure of claim 1 having each upper partition provided with an oil conducting groove leading to its edge, the support being provided with an oil passage 50 whereby oil may be fed through the passage into the housing above the upper partition and after falling upon the upper partition passed through the groove into the brush-receiving pockets.

In testimony whereof I have hereunto set 55 my hand.

WILLIAM R. MILLER.
